UNITED STATES PATENT OFFICE

123,693

DESIGN FOR A LIGHT-SENSITIVE OIL BURNER CONTROL UNIT

Frank E. Herr, Lancaster, Pa.

Application February 5, 1940, Serial No. 90,055

Term of patent 14 years

To all whom it may concern:

Be it known that I, Frank E. Herr, a citizen of the United States and a resident of Lancaster, in the county of Lancaster and State of Pennsylvania, have invented the new, original, and ornamental Design for a Light-Sensitive Oil Burner Control Unit, of which the following is a specification.

Reference is had to the accompanying drawing, forming part thereof, in which:

Figure 1 is a perspective view of one end of a

light-sensitive oil burner control unit, showing my new design.

Figure 2 is a partially inverted perspective view of the light-sensitive oil burner control unit, illustrating another aspect of the mounting.

The characteristic features of the design are illustrated in full lines.

I claim:

The ornamental design for a light-sensitive oil burner control unit, as shown and described.

FRANK E. HERR.
